UNITED STATES PATENT OFFICE

2,509,675

TREATING PLASTIC CONCRETE PAVEMENTS

Stephen J. Cox, Westfield, N. J., assignor, by
mesne assignments, to Worthington Pump and
Machinery Corporation, Harrison, N. J., a cor-
poration of Delaware

Application July 19, 1945, Serial No. 605,883

5 Claims. (Cl. 94—46)

1

The improvements relate to devices and methods for making pavements of concrete in which hydraulic cement is the bonding element, and particularly to devices for mechanically treating and finishing the wet plastic concrete after it has been mixed, deposited and spread on the subgrade of the roadway and before it has had time to set and form the concrete slab providing the finished surface of the pavement.

The primary objects of the improvements are to provide improved means for compacting or consolidating the aggregates of the plastic concrete—usually Portland cement, sand and small stone or gravel mixed with a small percentage of water—eliminating excess water and air from the mass and forming a firm body of uniform maximum strength throughout with a smooth wear and shock resisting surface, while preserving the intimate and equal mixture and distribution of coarse and fine aggregates and without causing deterioration of the bonding elements or impairing the action of entrained air where air-entraining cement is used.

This is accomplished in the present improvements by subjecting the surface of the plastic concrete to the action of a plurality of relatively light rollers provided with uniform alternately undulating or corrugated surfaces passed over it but not exercising substantial pressure thereon or sinking bodily therein and exercising a mild working and agitating or quaking effect thereon which extends in a greater or lesser degree through the body thereof.

This action involves a method or process of treating the concrete for the purposes stated which may be carried out by other devices than those herein described and shown, but provided with means for shifting them laterally at the end of a stroke or strokes, so that the low ridges and shallow grooves are reversed or counteracted by succeeding strokes or reciprocations, each ridge being thus succeeded by a groove and vice versa and the aggregates thus being given a lateral movement alternately in opposite directions.

In the said drawings, Fig. 1 is a plan of a mechanism embodying the mechanical invention and adapted to perform the method or process;

Fig. 2 is a vertical, medial, longitudinal section of the first roller, showing the bottom part only;

Fig. 3 is a like section of the second roller;

Fig. 4 is a rear end view of the mechanism of Fig. 1, with one side frame member partly in vertical section;

Fig. 5 is a side view of the same with the strike-off and screed omitted;

Figs. 6 and 7 are front and side views respectively of detached portions of the same showing strike-off and screed devices.

Referring to the said drawings, 1 and 2 are hollow imperforate rollers of relatively thin sheet

2

metal weighing when at ten inches in diameter and ten feet in length not substantially more than ten percent of the same mass or bulk of concrete, riding on the surface of the plastic concrete as they pass over it and not sinking into it to any material extent. They are provided with annular corrugations formed by projections 3 and indentations 3' on 1 and 4 and 4' respectively on 2 of uniform depth, width and contour, giving their surfaces a regular wave-like character longitudinally. The depth of the corrugations is exaggerated, as shown. The corrugations of the two rollers are of the same size and shape but are alternated or staggered with respect to each other so that the projections 3 on roller 1 are opposite the indentations 3' of 2 and the projections 4 on 2 are opposite the indentations 3' of 1. The result of this formation and arrangement is that as the rollers pass over the surface of the plastic concrete the first roller produces therein slight longitudinal grooves or depressions 5 with slight ridges 5' between them (Fig. 2) and the second or following roller displaces and obliterates these grooves and ridges and supplants them with ridges 6 and grooves 6' respectively (Fig. 3) of its own, both rollers moving the concrete aggregates at the surface laterally in these operations as well as to a certain extent vertically and causing agitation of the entire mass.

It will be observed that the corrugations of the rollers are such that if the rollers are brought together in their longitudinal operating positions their corrugations will mesh and coincide so that there will be an uninterrupted line of contact between their opposed surfaces. This duplication of the corrugations insures uniform treatment of the concrete throughout its entire body and a resulting uniform cross section of texture and strength. It also insures the uniform compacting of the mass and elimination of excess water and air pockets. Whether and in what manner, if at all, this duplication can be departed from without producing undesirable results can only be determined by careful tests. It is known, however, that excellent results are obtained by adhering to it and that some, at least, departures from it will produce unsatisfactory results.

The staggered arrangement of the ridges and grooves of the rollers so that they will act alternately on the concrete as the rollers pass back and forth over it is of the greatest importance as it produces a uniform "kneading" action in which the aggregates are agitated or vibrated vertically and in all directions longitudinally and laterally, so that no portion of the mass can escape this action and all parts are subjected to it equally. This causes the larger aggregates to settle to a limited extent and together with smaller aggregates to fit into the interstices between them, as can be observed by the slight

shrinkage of the mass when treated and by observing a broken slab so treated after setting.

The corrugations of the rollers are quite shallow and can be from one-half to one quarter inch, from the base of each ridge—or the bottom of the groove separating it from the next—to its apex radially, depending on the character and size of the concrete aggregates to some extent. They are also relatively wide longitudinally of the roller and are from peak to peak a little in excess of the greatest diameter of the largest aggregates, so that these aggregates cannot span them.

The contour of the corrugations is a series of smooth reversed curves on relatively long radii, as shown, and their surfaces are free from sharp edges or abrupt deviations from such curvature.

Two rollers are shown in the illustrative embodiment, but more may be used if desired or found advantageous for the particular use intended. And they are rolled back and forth over the surface of the plastic concrete as many times as may be found necessary to produce the desired finishing and compacting effect, and the elimination of air voids and excess water. The rollers are spaced apart far enough to give clearance and insure against contact between them, but their exact spacing is not important. They should usually, however, follow one another rather closely, and the strike-off blade preceding the forward roller and the screed following the second roller, hereinafter described, should also follow and precede their respective rollers without unnecessary spacing. This prevents the accumulation of liquid or "soup" in the grooves formed by the rollers and maintains its even distribution over the surface of the concrete. The same result may be attained, however, by operating the device at a sufficient speed, regardless of spacing.

The working of the surface of the concrete by the rollers also tends to open up momentarily small crevices between the large aggregates in some places so that the liquid element of the concrete does not exude therefrom to an undesirable extent or form a film of laitance over the surface.

The rollers rotate freely and in unison as they roll over the surface of the concrete but should there be for any reason a small amount of slippage it will not seriously affect their operation or the performance of their functions. It is therefore not necessary that they be geared together, as by sprockets and chains.

The rollers 1 and 2 are mounted by axial trunnions 10 in slotted bearings 11 on the side frame members 16 of the carriage 7, running on flanged wheels 8 on side forms 9, and therefore are free to move up and down to a limited extent. This permits them to impose only their own weight on the concrete, the weight of the carriage and other parts carried thereby being borne by the said side forms.

At the forward end of the carriage 7 there is mounted on the carriage a strike-off blade 12 by means of screw bolts 13 passing through adjustment slots 14 and into the end pieces 15 of the carriage frame. This strike-off is therefore mounted for limited vertical adjustment to accommodate itself to the level of the concrete, and to the bottom of the corrugated rollers. It normally has its lower edge a little above the bottom of the rollers and slightly above the upper edges of the side forms 9 and extends across the strip of pavement to be finished, so that it 76

will strike off the concrete leaving a sufficient margin for shrinkage from the finishing operation and can be positioned intermediate the top and bottom of the corrugations, so that when the rollers are moved backward it will level off the ridges and grooves left by the rollers, shearing off the former and filling in the latter and thus restore the smooth upper surface of the concrete strip. At the rear of the carriage is mounted a screeding blade 19 of the same character as the strike-off 12 and mounted in the same manner, so that when the rollers are moved forward the upper surface of the concrete is leveled by this screed following the roller 2 and as they are moved backward the same function is performed by the strike-off blade following the roller 1. The rollers have end spacing members 21, extending between their ends and the side frame members and corresponding approximately with the thickness of the flanged wheels 8.

The rollers 1 and 2, the strike-off and screed 12 and 19 may all be slightly curved or beveled longitudinally to provide the concrete strip upon which they operate with a suitable crown. The frame or carriage is completed by the top cross strips 23 and 24.

Various changes in the details of construction and arrangement of the exemplary embodiment herein shown and described may be made without departing from the scope of the invention, and various devices for spreading, striking off, screeding, straightedging, belting and final "broom" finishing may be used in conjunction or cooperation therewith. It will be seen, however, that the invention provides means for consolidating and finishing the plastic concrete, eliminating excess water and air and producing uniform density and compaction without tamping, agitating or vibrating it violently and thus interfering with the arrangement, concrete producing efficiency or uniform texture of the aggregates. This is highly desirable in the finishing of all Portland cement concrete, especially concrete in which air-entraining cement is employed.

The rollers may be rolled crosswise as well as lengthwise of the plastic concrete pavement or one way or the other, if desired, or found necessary or advisable to produce a desired result.

The rollers are also preferably made removable and replaceable by mounting their trunnions in slots formed in outwardly and upwardly inclined side frame members so that the rollers may be lifted out of the upper part of the vertical slots and other rollers then placed in the slots by passing their trunnions down thereinto. In this manner rollers having different weights, form and diameter or different corrugations may be used for different purposes, as to fit the crown of the road or curves or unusual grades. Such a construction is shown at 22.

It will be understood also that the spacing of the rollers and the instrumentalities preceding and following them may be varied to avoid interference with their action by picked up portions of the concrete, should such a thing occur, and to give full clearance for cleaning. These instrumentalities may be of any suitable form and may operate in any suitable manner to perform their respective functions properly.

On pavements where a slightly corrugated surface is desirable, as at some airports to increase visibility or give greater braking power and on some unusual road grades to improve traction and drainage, the screeding may be omitted, and

the pavement will be found to be well compacted and finished by the action of the rollers. The main finishing rollers may be followed up by rollers having very shallow grooves and ridges. This may also be done prior to screeding, to reduce the leveling work required of the screed.

I claim:

1. A device for finishing plastic hydraulic cement concrete pavements comprising a plurality of relatively light radially corrugated rollers mounted to rotate on parallel axes in approximately the same plane, the corrugations of one roller being arranged in staggered relation to those of the next roller so that the ridges of one roller are opposite the depressions of the next and vice versa, whereby the rolling of said rollers successively over the surface of the plastic pavement will thereby form in the surface of the pavement alternating ridges and grooves by displacing the aggregates vertically and laterally with the projecting ridges of the rollers, a carriage on which said rollers are mounted to rotate and bearings thereon for the axes of the rollers, said bearings provided with elongated openings to permit limited vertical movement of the roller axes independent of the carriage.

2. A device for finishing plastic hydraulic cement concrete pavements comprising a plurality of relatively light radially corrugated rollers mounted to rotate on parallel axes in approximately the same plane, the corrugations of one roller being arranged in staggered relation to those of the next roller so that the ridges of one roller are opposite the depressions of the next and vice versa, the corrugations of said rollers extending annularly about the rollers and merging each into the adjacent one by arcuate surfaces to present a continuous sinuous surface for contact with the hydraulic cement whereby the rolling of said rollers successively over the surface of the plastic pavement will thereby form in the surface of the pavement alternating ridges and grooves by displacing the aggregates vertically and laterally with the projecting ridges of the rollers, a carriage on which said rollers are mounted to rotate and bearings thereon for the axes of the rollers, said bearings provided with elongated openings to permit limited vertical movement of the roller axes independent of the carriage and said corrugations forming in effect relatively shallow waves or undulations of uniform size and contour running lengthwise of the rollers.

3. A device for finishing plastic hydraulic cement concrete pavements comprising a plurality of relatively light radially corrugated rollers mounted to rotate on parallel axes in approximately the same plane the corrugations of one roller being arranged in staggered relation to those of the next roller so that the ridges of one roller are opposite the depressions of the next and vice versa, the corrugations of said rollers extending annularly about the rollers and merging each into the adjacent one by arcuate surfaces to provide a continuous sinuous surface for contact with the hydraulic cement whereby the rolling of said rollers successively over the surface of the plastic pavement will thereby form in the surface of the pavement alternating ridges and grooves by displacing the aggregates vertically and laterally with the projecting ridges of the rollers, a carriage on which said rollers are mounted to rotate and bearings thereon for the axes of the rollers, said bearings provided with

elongated openings to permit limited vertical movement of the roller axes independent of the carriage, and a strike-off blade mounted on the carriage in advance of said rollers.

5. A device for finishing plastic hydraulic cement concrete pavements comprising a plurality of relatively light radially corrugated rollers mounted to rotate on parallel axes in approximately the same plane, the corrugations of one roller being arranged in staggered relation to those of the next roller so that the ridges of one roller are opposite the depressions of the next and vice versa, the corrugations of said rollers extending annularly about the rollers and merging each into the adjacent one by arcuate surfaces to provide a continuous sinuous surface for contact with the hydraulic cement whereby the rolling of said rollers successively over the surface of the plastic pavement will thereby form in the surface of the pavement alternating ridges and grooves by displacing the aggregates vertically and laterally with the projecting ridges of the rollers, a strike-off mounted on the carriage in advance of the rollers and a screeding device mounted behind the said rollers, said screeding device and strike-off adjustably mounted on the carriage and adjustable to the surface of the cement being pressed, smoothed and treated.

5. A device for finishing plastic hydraulic cement concrete pavements comprising a plurality of relatively light radially corrugated rollers mounted to rotate on parallel axes in approximately the same plane, the corrugations of one roller being arranged in staggered relation to those of the next roller so that the ridges of one roller are opposite the depressions of the next and vice versa, the corrugations of said rollers extending annularly about the rollers and merging each into the adjacent one by arcuate surfaces to provide a continuous sinuous surface for contact with the hydraulic cement whereby the rolling of said rollers successively over the surface of the plastic pavement will thereby form in the surface of the pavement alternating ridges and grooves by displacing the aggregates vertically and laterally with the projecting ridges of the rollers, a strike-off mounted on the carriage in advance of the rollers and a screeding device mounted behind the said rollers said strike-off and screeding devices being adjustable to the surface of the cement being pressed, smoothed and treated.
